Primary Examiner — Mark A Goodwin*Assistant Examiner* — William B Melliar(74) *Attorney, Agent, or Firm* — Hudak, Shunk & Farine Co. LPA(57) **CLAIM**

The ornamental design for a “lighted mirror assembly”, as shown and described.

DESCRIPTION

FIG. 1 is a front view of a lighted mirror assembly showing my new design;

FIG. 2 is a rear view thereof;

FIG. 3 is a right front perspective view thereof;

FIG. 4 is a left rear perspective view thereof;

FIG. 5 is a right side view thereof, with the left side being a mirror image and therefore not shown; and,

FIG. 6 is a top view thereof, with the bottom view being a mirror image and therefore not shown.

The broken lines in the drawings depict portions of the lighted mirror assembly that form no part of the claimed design.
